UNITED STATES PATENT OFFICE.

IRA T. ENGLISH, OF PORTLAND, OREGON.

SACK-HANDLING MACHINE.

Application filed March 19, 1924. Serial No. 700,200.

To all whom it may concern:

Be it hereby known that I, IRA T. ENGLISH, a citizen of the United States, and a resident of Portland, in the county of Multnomah and State of Oregon, have invented a new and useful Sack-Handling Machine, of which the following is a specification.

This invention relates to the handling of grain and similar materials.

An object of my invention is to provide an exceedingly simple and efficient sack handling machine which will transport sacks of grain horizontally or up an incline, and empty the sack of its contents at a given point.

A second object is to provide means for holding the sack while emptying.

A third object is to provide means for assembling emptied sacks in shape for securing same in bundled form, or for sorting. A fourth object is to so construct the machine that its point of emptying can be readily varied.

25 I accomplish these results in the manner set forth in the following specification and illustrated in the accompanying drawings, in which:

Figure 1 is a side elevation of my device on a reduced scale of which Figure 2 is a front elevation and Figure 3 is a plan. Figure 4 is a vertical section along the line 4—4 in Figure 1. Figure 5 is an enlarged vertical section along the line 5—5 in Figure 6. Figure 6 is a vertical section taken along the line 6—6 in Figure 5. Figure 7 is a section along the line 7—7 in Figure 5. Figure 8 is a perspective of the bag assembling device.

40 Similar numbers of reference refer to the same parts throughout the several views.

Referring in detail to the drawings, I have illustrated my device as mounted on a base consisting of the horizontal members 10 which are joined at their forward end by a tie 11. The members 10 and 11 are supported by the casters 12.

Against the inner side of the members 10 I have hinged the upright standards 13 on the shaft 14 whose outer end is provided with a sliding handle 16 and a ratchet wheel 17 which engages a pawl 18 on one of the members 10. Cable drums 19 are secured on the shaft 14. On the inner sides of the upper ends of the standards 13 I have mounted the pulleys 20 on the shaft

21, which also serves as a tie between the members 13. Cables 22 wind around the drums 19 and pass over the pulleys 20.

On the rear end of the members 10 I have mounted the bearings 23 which carry the shaft 24, which also serves as a tie between the members 10. On the center of the shaft 24 is placed a wide pulley 25. Between the pulley 25 and the bearings 23 I have placed the bearings 26 on which are slidably mounted the two angle irons 27 provided with a spacer 28 whose screw 29 bears against the bearing 26 and serves as a tightener. Spacer collars 30 are placed between the members 25 and 26 and spacer collars 31 are placed on the shaft 24 between the members 23 and 26.

The forward ends of the angle irons 27 are separated by the bearing blocks 32 and secured thereto. A shaft 33 bears in the blocks 32 and has on one end a large sprocket 34. A wide pulley 35 is secured on the shaft 33 and a wide conveyor 36 passes around the pulley 25 and 35 and can be driven by the sprocket 34. A floor 37 is provided under the upper run of the conveyor 36. Suitable upright supports 38 for the floor 37 are mounted on the angle irons 27.

Between the members 27 is mounted a counter shaft 39 whose sprocket 40 drives the sprocket 34 through the chain 41. On the counter shaft 39 is also placed a pulley 42 which is driven through the belt 43 by the motor 44 which is mounted on the raised base 45 sufficiently high to permit sacks of grain on the conveyor 36 to pass freely under same.

Attached to the lower members 27 is a transverse angle iron 46 from which is hung the arms 47 whose bent lower ends 48 are secured to a horizontal T iron 49. Slidably placed on the member 49 is a sack gathering or assembling frame 50 provided with a handle 51 and the long straight needles 52 which are held practically parallel to the lower run of the conveyor 36. On the conveyor 36 is placed a plurality of sack supports 53. Each support 53 has its lower edge curled to receive a pivot 54 which is supported by the standards 55 formed on the strap 56 which, in turn, is secured to the conveyor 36. A similar strap 57 is secured to the conveyor 36 a short distance from the strap 56 and carries the brace rods 58 which engage the curl 59 on the up-

per end of the sack supports 53. These braces hold the member 53 rigid with relation to the conveyor 36 and yet permit its easy movement around the pulleys 25 and 35.

5 On the rear side edges of the members 53 are secured the bearings 60 which carry a pivotally mounted flat bar 61 provided with rounded ends 62 which journal in the bearings 60. Each bar 61 is provided with 10 curved needles 63 which are bent on a radius whose center is the axis of the shaft end 62. On one of the ends 62 I have secured a rocker arm 64 provided with a roller 65 which can engage the somewhat blunt ends 15 66 of the angle iron track 67, and in riding upon said track cause said curved needles to be passed through the sack support and the bottom of any sack which may be resting upon same. The track 67 is supported 20 on the brackets 68 from the angle irons 27. Each member 61 is provided with a spring 69 which holds the needles 63 on the rear side of the sack supports 53 when the roller 65 is not riding on the track 67.

25 The operation of my device is as follows: The conveyor 36 is operated by the motor 44 at a suitable speed, which would be in the neighborhood of sixty feet per minute, and the filled sacks 70 can be placed on the conveyor 36 against the sack supports 53. As the sacks are carried upward, the roller 65 comes in contact with the blunt end 66 which causes the needles 63 to be driven through the bottom of the sack. The sack 35 70 is now carried over the pulley 35 and emptied into the chute 71 supported by the arms 72 from the shaft 33. The emptied sack 73 is now dragged over the side of the chute 71 and carried down to the needles 52.

40 The track 67 ends at this point and the needles 63 are withdrawn from the sack 74, leaving it suspended on the needles 52.

Each oncoming sack 74 pushes its predecessor slightly further upon the needles 52, and when the needles 52 are supporting the desired number of sacks, the entire holder or frame 50 is withdrawn by means of the handles 51 which normally serve as a stop against the end of the member 49, and an empty frame 50 is put in its place. The sacks on the filled frame are now sewed together and the needles 52 withdrawn and the frame 50 made available for other sacks.

In this way no straightening of sacks is required and they are all put in shape for handling.

In some cases it may be preferable to tie these sacks, as is commonly understood, which, of course, would not interfere with 60 the operation of sack gathering.

I claim:

1. A sack emptying machine having, in combination, a conveyor; and a sack holding means on said conveyor adapted to en-

gage the closed end of open sacks while they 65 pass around the discharge end of said conveyor in an inverted position.

2. In a sack emptying machine, the combination of a conveyor; a plurality of sack holding means on said conveyor; and a sack 70 gathering means adapted to receive empty sacks from said holding means.

3. In a sack emptying machine, the combination of a conveyor; a plurality of sack supports placed transversely across said 75 conveyor; sack holding means on said supports; actuating means for said sack holders adapted to cause said holding means to hold said sack until it is emptied; and a sack gathering frame adapted to receive empty sacks from said sack holding means.

4. In a sack emptying machine, the combination of a tiltable conveyor having its loading end lowermost; means for driving said conveyor; sack supports placed transversely across said conveyor; sack engaging needles mounted on said supports; means for passing said needles through said sack after it is placed on said conveyor and to hold said sack on the bottom run of said conveyor 90 after it is emptied and to release said sack after it is carried past its point of discharge.

5. In a sack emptying machine, the combination of a conveyor with a plurality of sack supports fastened transversely across 95 said conveyor, each of said supports including a rocker shaft mounted on its rear side; curved sack engaging needles mounted on said shaft; a rocker arm on said shaft; a cam track mounted alongside of said conveyor adapted to rock said shaft by engaging said arm in a manner to pass said curved needles through said support into a filled sack, and to withdraw said needles along the under run of said conveyor after 100 said sack has been emptied.

6. In a sack emptying machine, the combination of a tiltable conveyor hinged at its lower end; a plurality of curved sack holding needles mounted on said conveyor; a needle actuating track mounted on the frame of said conveyor adapted to pass said needles through the bottoms of filled sacks on the upper run of said conveyor and withdraw said needles on the under run of 110 said conveyor.

7. In a sack emptying machine, the combination of a sack carrying conveyor; supports for filled sacks mounted on said conveyor; sack gathering needles on the under side of said conveyor; sack holding needles on said supports adapted to engage a sack on the upper run, and also during the emptying period, and to be withdrawn as the emptied sacks are deposited on said gathering needles.
